UNITED STATES PATENT OFFICE.

SAMUEL H. GARRETT, OF MANSFIELD, OHIO.

FENCE-MACHINE.

SPECIFICATION forming part of Letters Patent No. 376,521, dated January 17, 1888.

Application filed November 4, 1887. Serial No. 254,291. (No model.)

To all whom it may concern:

Be it known that I, SAMUEL H. GARRETT, a citizen of the United States, residing at Mansfield, in the county of Richland and State of Ohio, have invented certain new and useful Improvements in Fence-Machines, of which the following is a specification, reference being had therein to the accompanying drawings.

This invention has relation to machines for weaving picket-and-wire fences, and more particularly to that class thereof in which a series of twisters are operated by a rack-bar; and among the objects in view are to simplify the construction, reduce the number of parts, and facilitate the manufacture and combining of said parts, whereby a machine is provided at a reduced cost.

Other objects and advantages of the invention will hereinafter appear, and the novel features thereof will be particularly pointed out in the claims.

Referring to the drawings, Figure 1 is a side elevation of a machine constructed in accordance with my invention, the same being in operative position and in the act of forming a fence. Fig. 2 is a front elevation of the machine. Fig. 3 is a side elevation of a portion of a post provided with a tension device employed in connection with the machine. Fig. 4 is a transverse section on the line $x-x$ of Fig. 2. Fig. 5 is a detail in perspective, herein-after described, as is also Fig. 7. Fig. 6. is a transverse section on the line $y-y$ of Fig. 1, showing the mechanism for holding the machine and picket firmly in place while the twists are being made.

Like letters of reference indicate like parts in all the figures.

A represents the usual uprights, to which and at equal distances apart are secured, by means of bolts B', opposite clamping-plates B. The plates B are preferably cast, and are formed with bearings B², in which are journaled the usual perforated and toothed twisters, B³. The ends of said plates are formed at an angle to the remainder of the plate, and are adapted to embrace and form guides for a rack-bar, C, interposed between the bent ends and said twisters and adapted to mesh with and rotate the latter. The upper and lower pair of plates B are arranged with their terminal

ends near or in contact with each other, and against said plates are designed to abut stops C, arranged near each end of the rack-bar C, so that its upward and downward movement 55 is limited, by which the requisite number of rotations are given to the twisters and imparted to the strands composing the fence. At about the center of the upright A are secured, by means of the bolt B', clamping- 6c plates D D'. The plate D' is similar in construction to the plates B, but the plate D differs in that a bearing, D², is formed at a right angle to and at the outer edge thereof, in which is journaled a miter-gear and its shaft D³, which 65 gear is operated by a crank, D⁴, affixed to the opposite end of the shaft. The twister employed with this pair of plates also differs from the remaining twisters in that its hub or boss is provided with a miter-gear, B⁴, adapted 70 to mesh with the gear D³, just described. In this manner, by rotating the handle D⁴, motion is imparted to the shaft and gear D³, thence to the gear B⁴ and its twister B³, and to the rack-bar C, and the remaining twisters, all 75 clearly shown in Figs. 1 and 2 of the drawings, E representing the pickets around which the strands of wire are being woven.

In Figs. 1, 6, and 7 I have shown a device for holding the machine firmly in place while 80 the twists are being made.

F represents an angular casting or plate, which is adapted to be bolted to the front of the upright A and extends around to one side and has formed thereon ears or lugs F', which 85 form bearings for a toothed sector, F², the teeth of which are adapted to take into and thus operate the arm or clasp F³, having perforations along its surface in which the teeth of the sector F² operate. Upon the opposite 90 angle of the plate F are formed guides or ways F⁴, by which the forward bent end of the clasp F³ is held in rear of the machine.

A picket E having been placed in position, the machine is operated until the rack-bar C 95 has reached that point where one of the stops C' comes into contact with the clamping-plates at the top or bottom of the machine. The machine is then moved forward and another picket is placed in position between the wires. 100 The last picket that was woven in is caught by the clamp, and by swinging the sector-lever

until the teeth thereof take into the apertures of the clamp-bar the machine and last-adjusted picket are held firmly in their place. The crank of the machine is then revolved in a reverse direction until opposite stop, C', abuts against the clamping-plate at the opposite end of the machine.

The sector F² is provided with a plain face, so that when swung upon its pivot until said face is adjacent to the spacing-bar said bar may be freely slid within the ways F⁴, and can be held at any point by simply swinging the sector-lever until the teeth thereof take into the teeth of apertures in the clamp-bar. By this device the twisting of the wire between the pickets is rendered uniform and can be done with perfect ease.

Referring to Fig. 3 of the drawings, G represents in this instance one of the posts comprising the fence or other suitable support, and H a tension device, a series of which are to be mounted on said posts or support in advance of the machine; or it may be upon any other post, the number of tensions being in accordance with the number of twisters employed in the machine.

The tension consists of a simple casting or plate, H', perforated and adapted to be secured, by screws or other fastening devices, to the face of said post. An opening, H², is formed in the plate, and at either side thereof within said plate are formed parallel grooves H³, through which the strands I of wire are adapted to pass on their way to the machine. A button, H⁴, is secured to the post in the center of the plate, or it may be to the plate, which will bind upon the strands and provide and maintain sufficient tension. By the provision of the parallel grooves H³ the strands of wire are prevented from being bent, which, if done, would necessarily impede their easy passage through the apertures in the twisters. This tension may be light or heavy, it being graduated by screws H⁵, passing through the button.

It is apparent that all of the plates, &c., composing the machine may be easily cast and assembled, and this without any special hand or machine finishing.

Having described my invention and its operation, what I claim is—

1. In a fence-machine, the combination, with the upright A, having the plates B bolted thereto, said plates being bent at their ends and having the gear-twisters B³ journaled therein, of the rack-bar C, embraced by said bent ends, and having stops C' arranged thereon and adapted to limit the movement of the bar by coming into contact with the said bent ends, substantially as specified. 55

2. In a fence-machine, the combination, with the upright A, having the plates B and gear-twisters B³, and the rack-bar C, embraced by said plates and meshing with the twisters, of the plates D and D', the former having the bearing D² formed at a right angle thereto and carrying the gear D³ and handle D⁴, the twister B³, mounted in said plates, and the gear B⁴, mounted on the twister and meshing with the gear D³, substantially as specified. 65

3. In a fence-machine, the combination, with the upright A, of the casting F', carrying the sector F², and having the ways F⁴, and the clamping-bar F³, mounted in said ways and adapted to mesh with said sector, substantially as specified. 70

4. In a fence machine, the combination, with the upright A, of the casting F', having guides F¹, the clamping-bar F³, mounted therein, and the lugs or ears F', carrying the sector F², having the toothed and plain faces, substantially as specified. 75

5. The combination, with the fence machine and its twisters, of the tension H, consisting of the plate H', having the central opening, H², and parallel grooves H³, for carrying the wires, and the button H⁴, adapted to bind upon said wires, substantially as specified. 85

6. In combination with a fence-machine and the post G, a tension device comprising the securing-plate H', having the central opening, H², and grooved, as at H³, and the button H⁴ and its screw H⁵, substantially as specified. 90

In testimony whereof I affix my signature in presence of two witnesses.

SAMUEL H. GARRETT.
